UNITED STATES PATENT OFFICE.

BASSLER BOYER, OF LEBANON, PENNSYLVANIA.

CAR-BRAKE.

SPECIFICATION forming part of Letters Patent No. 394,452, dated December 11, 1888.

Application filed September 13, 1888. Serial No. 285,299. (No model.)

To all whom it may concern:

Be it known that I, BASSLER BOYER, a citizen of the United States of America, residing at Lebanon, in the county of Lebanon and 5 State of Pennsylvania, have invented new and useful Improvements in Car-Brakes, of which the following is a specification.

My invention has relation to car-brakes; and the objects are to provide a car-brake of 10 simple and durable construction, to increase the power, and to enhance the efficiency of the mechanism. This I accomplish by grouping with the brake-bars carrying the brake-shoes and operative levers rotary elliptical 15 disks, as hereinafter specified.

I have clearly and fully illustrated my invention in the accompanying drawings, where-
in—

Figure 1 is a bottom plan view of a car- 20 body having my improved brake connected thereto and showing the relative positions of the brakes on and off. Fig. 2 is a transverse sectional view taken through the line *x* *x* of Fig. 1, showing the brakes off; and Fig. 3 is 25 a similar view taken through the line *y* *y* of Fig. 1, showing the brakes on.

Reference being had to the drawings, A designates the bottom of the car, having the requisite bottom timbers, 1, and a central 30 cross-timber, 2, on the latter of which the operating-levers are shown pivotally fulcrumed.

B designates the trucks, the wheels of which are supported on axles having bearing-boxes, as usual.

35 C designates a cross-timber attached to the bottom of the car between the wheels of the trucks, and constituting a timber to which links connected to the brake-bars are attached.

40 Immediately below the cross-timber C is arranged another cross-piece, D, a space being left between these two timbers for the purpose of affording room within which to dispose the disks.

45 E designates the brake-bars, suspended by links 3 from the cross-timber C. These brake-bars are provided with brake-shoes 4 of any of the usual approved kinds. In the middle rear part of the brake-bars are attached or 50 formed thereon bearing-blocks 5, having their inner edge faces concaved to conform to the

sides of the elliptical disks, substantially as shown in the drawings.

F designates the elliptical disks, made of any suitable material having strength sufficient to withstand the intended uses. These elliptical disks are mounted on vertical shafts 6, having suitable bearings in the timbers, or have their lower ends fixed in hangers on the upper timber. The disks are made of such 55 width in transverse section as that when arranged with their longitudinal center in the direction of the cross-timbers the brake-bars will swing inward and leave the brake-shoes free from the wheels, as shown in Fig. 2 of 60 the drawings.

To restrain the too rapid turning of the disk in applying the brakes and to return the disks to a position of "off-brakes" when the power has been disconnected or released, a spring, 7, is connected to the disk, the force of which restrains its rotation and bears to throw the disk in reverse movement to that exerted by the power. As a spiral spring arranged with torsional force or a straight spring may be 75 with equal utility applied, I have shown both varieties applied, the first-named being arranged above the disk and the latter below. Of course in practice but one is used.

Power may be applied to rotate the disks 80 and apply the brakes either by the hand-brake staff or by the steam or air brake appliances, or both in conjunction. The hand-brake leverage is designated by a rod, 8, connected to one end of the disk, the other 85 end of said rod being connected to a lever, 9, mounted on a bearing and having the upper end connected to the rod 10, which is connected to the one end of a lever, 11, mounted on the bottom of the car. At 90 the other end of the lever 11 is connected the brake-rod 12, having connection with the brake-staff on the platform of the car. I have not shown this last connection, as it is so well known as to not require special description 95 or illustration. The piston 13 of the steam or air brake apparatus 14 is connected to the lever 11, to which is connected one end of a rod, 15, having its other end connected to the disk substantially as shown in Fig. 1 of the 100 drawings, the lever connections and movements in this relation being shown in dotted

lines. The interposition of the vertically-arranged lever 9 is intended to provide connections to the disks, which will turn them on a horizontal plane and avoid torsional strains; 5 but in a connection involving a direct attachment to the disks these levers may be dispensed with.

Having thus described the mechanism involved, I now proceed to particularly point out 10 and distinctly claim the parts, improvements, and combinations which I claim as my invention, as follows:

1. The combination of the pivotally-supported rotary elliptical disks, the suspended 15 brake-bars, and a lever or rod to rotate the disk on its axis, whereby the brake-bars are spread apart and the brakes applied, substantially as described.

2. The combination of the pivotally-supported rotary elliptical disk, the suspended 20

brake-bars formed with concave bearing-blocks to be engaged by the disk, and a lever or rod to rotate the disk and spread the brake-bars, substantially as described.

3. The combination of the pivotally-mounted elliptical disk, the brake-bars formed with concave bearing-blocks to be engaged by the disk, a lever or rod to turn the disk to spread the brake-bars, and a spring on the disk to restrain the too rapid turning of the disk in 30 applying the brakes, and to return it to a normal position when the strain of the lever is thrown off, substantially as described.

In witness whereof I have hereunto set my hand in the presence of two attesting witnesses.

BASSLER BOYER.

Attest:

PETER HAUER,
S. G. HORST.
